UNITED STATES PATENT OFFICE.

FERDINAND FISCHER, OF BERLIN, GERMANY.

PRINTING PLATE AND METHOD OF PRODUCTION THEREOF.

Application filed March 10, 1926. Serial No. 93,758.

As printing plates for socalled office duplicators there are mostly used paper plates with a coating of wax or similar material. The use of such plates however entails a number of disadvantages.

For this reason some office duplicators have previously been produced which operate with more suitable printing plates of metal or metallized or metal-coated paper. 10 These printing plates are so thin that they can be typed upon in an ordinary typewriter just as an ordinary sheet of paper, whereupon printing is effected by means of the printing plate in the usual planographic or lithographic method, for example offset process.

Such metal printing plates have extraordinarily great advantages but some disadvantages were hitherto unavoidable.

20 If simply the raw metal plate is supplied to the purchaser as the printing plate, the purchaser in order to be able to operate with the plate, must himself treat the printing surface in the manner well known in the art of lithography. This includes graining the printing surface and etching before printing, which imparts to that part of the printing surface, not provided with inscriptions, images or lines for printing, the capacity of rejecting printing ink when in a damp condition.

25 The production of good and uniform graining, however, is a very difficult operation on thin sheet material so that an insufficiently skilled purchaser or user will spoil a great many plates.

In order to remedy this disadvantage it has already been suggested to supply to the purchaser from the factory completely prepared plates, that is grained and etched printing plates, which consequently when in a damp condition reject printing ink over their entire surface. This however has the disadvantage that the typing or marking of 45 the written matter causes considerable difficulties, and necessitates the use of specially prepared carbon papers, heat treatment and the like.

The invention eliminates all these difficulties, in that it suggests a novel middle course. According to the invention the purchaser or user is supplied with the finished grained printing plate, which however has not been etched, as a new article of manufacture. 50 The purchaser need not therefore be troubled with the difficult process of graining or

roughening and is therefore not liable to spoil the plate in carrying out this operation. On the other hand he can type upon the half finished plate as on an ordinary sheet of paper, in a typewriter and then without any other treatment, except simply that of etching, in the manner well known in the art of lithography, render it suitable for printing. 60

When referring hereinafter to "small" 65 printing plates, this term is intended to include printing plates up to about the size of a normal sheet of writing paper, therefore up to about 21 cm. wide and 33 cm. in length.

In the accompanying drawings there is 70 diagrammatically illustrated one constructional example of the invention and a particularly advantageous method of production. The invention however is not limited in any way thereto.

75 Fig. 1 is a plan of a printing plate according to the invention on a reduced scale.

Fig. 2 is a section of a part of the printing plate to a larger scale.

Fig. 3 is a section of a graining device. 80

Fig. 4 is a section of a modified form of graining device.

The printing plate *a* is along its two narrow sides provided with a plurality of holes *b* for the purpose of attachment to suitable pins of the cylinder of an office duplicator, and preferably consists of an extremely thin plate of a metal suitable for lithographic purposes such as zinc or aluminum, for example only about 0.05 to 0.06 mm. thick. 85 For the purpose of more convenient manipulation this plate is coated on the rear side with a sheet *c* of paper or the like soft material.

According to the invention the consumer 90 is supplied with the sheet cut to a useful size and provided with holes *b* in such a condition that the printing surface is already provided with the graining *d*, which for the sake of clearness is shown by a thick line. 100

The production of this graining of the ready cut small sheets *a* would be extremely difficult in practice. For this reason recourse is had, according to the invention, to special treatment as represented in Figs. 105 3 and 4, according to which a plurality of printing plates are grained in the form of a large combined sheet or band and then cut into the separate printing plates.

According to Fig. 3 a large plate *g* is 110 clamped in a suitable manner on a rotary cylinder *f*, whose surface corresponds to

that of a plurality of printing plates *a*. Against the surface of the sheet *g* is projected a sand blast *h*, for example by means of projecting wheel *i*, whereby the surface 5 is grained. The sheet *g* is then cut into small plates *a*.

In the method of production according to Fig. 4 a long band *k* passes from a supply roller *m* over a drum *n* through the sand- 10 ing chamber *o* in which two projecting wheels *i'*, *i''* produce the graining by means of a sand blast in a similar manner as described in connection with Fig. 3, where- 15 upon the band is wound up on to the roller *p*, in order to be then cut into plates *a*.

What I claim and desire to secure by Letters Patent of the United States is:—

As a new article of manufacture, a small printing plate suitable for lithography comprising a metallic sheet provided with a 20 commercially grained printing surface, and of uniform thinness throughout to both end edges thereof, said sheet being of such thinness as to be successfully tensioned on the cylinder of a duplicating machine by mere 25 pins and holes, the end of said sheet being provided with a series of holes for this purpose extending transversely there across.

In testimony whereof I affix my signature.
FERDINAND FISCHER.
